UNITED STATES PATENT OFFICE.

LLEWELLYN H. STARKEY, OF NEW YORK, N. Y.

DESIGN FOR A DIAL.

No. 40,128.

Specification for Design.

Patented July 6, 1909.

Application filed March 25, 1909. Serial No. 485,857. Term of patent 14 years.

To all whom it may concern:

Be it known that I, LLEWELLYN H. STARKEY, a citizen of the United States, and a resident of New York, in the county of New York and State of New York, have invented a new, original, and ornamental Design for Dials, of which the following is a specification, reference being had to the accompanying drawing, forming part thereof.

The figure is a plan view of a dial showing my new design.

I claim:

The ornamental design for a dial, as shown.
